CLAIM

The ornamental design for a tulip-shaped hand tool grip, as shown and described.

DESCRIPTION

FIG. 1 is an isometric view of the tulip-shaped hand tool grip; FIG. 2 is a front view of the tulip-shaped hand tool grip; FIG. 3 is a back view of the tulip-shaped hand tool grip; FIG. 4 is a top view of the tulip-shaped hand tool grip; FIG. 5 is a bottom view of the tulip-shaped hand tool grip; FIG. 6 is a left side view of the tulip-shaped hand tool grip; and,

FIG. 7 is a right side view of the tulip-shaped hand tool grip. The phantom lines shown in the drawings represent environmental structure and form no part of the claimed design.
